ACCUMULATING MECHANISM

Horace S. Beattie, Poughkeepsie, and Francis E. Hamilton and George F. Daly, Endicott, N. Y., assignors to International Business Machines Corporation, New York, N. Y., a corporation of New York

Application October 17, 1946, Serial No. 703,752

3 Claims. (CL 235—61.6)

1

This invention relates to accounting machines and more particularly to the accumulating mechanism thereof.

The principal object of the invention resides in the provision of improved control mechanism for an accumulator, whereby coded or combinational designations on a record card representative of the digits may control the advance of an adding wheel to any of ten rotative positions.

In the accumulator to which the invention is applied, there is provided an adding wheel for each denominational order, with magnetically controlled coupling mechanism through which the wheel is driven from a constantly running drive shaft. Coupling is effected under control of card designations and, after the wheel has rotated, a magnetically controlled uncoupling mechanism causes it to stop. In handling combination designations wherein each designation has an assigned value constituting a component of the digit represented, it has been heretofore proposed to cause each designation to separately and in succession enter its assigned value (which is a component of the digit represented), so that a digit is entered in the wheel by one or more start and stop operations to sum up the separate values.

The present invention proposes to control the start and stop operations for certain of the digits, so that a first designation of a combination will cause a start operation and a succeeding designation of a predetermined value will negative an invariable stop operation, so the wheel will continue to rotate and merge two steps into one.

Specifically, the adding wheel is controlled by designations combinationaly represented by a 2, 1, 2, 5 code with these positions sensed in the order named, to start rotation of the adding wheel. Concurrently with the sensing of the second 2 position, the stop mechanism is invariably operated and, if there happens to be a designation in such second 2 position, the stopping action is prevented.

A specific object of the invention is to provide an accumulator wheel with a coupling mechanism effective to start rotation of the wheel, and an uncoupling mechanism effective thereafter to stop such rotation and control devices responsive to a record designation to negative the stopping action.

Other objects of the invention will be pointed out in the following description and claims and illustrated in the accompanying drawings, which disclose, by way of example, the principle of the

2

invention and the best mode, which has been contemplated, of applying that principle.

In the drawings:

Fig. 1 is a view in side elevation of the essential operating elements of one denominational order of the accumulator.

Fig. 2 is a detail view of the driving clutch mechanism.

Fig. 3 constitutes a wiring diagram of the circuits for controlling the operation of the accumulating mechanism.

Fig. 4 is a timing diagram.

The card

15 In Fig. 3 is shown a portion of a record card 10 provided with vertical columns in which the digits 1 to 9 may be recorded by perforations made in a set of four horizontal rows having the values 2, 1, 2, 5 as shown. It is diagrammatically indicated that the card 10 is advanced by feed rollers 11 to pass a row of sensing brushes 12 and that, after data perforations on one card have passed the brushes, there is an interval, following which corresponding perforating positions on a following card pass the brushes. The interval between the lowest perforating rows of the successive cards is termed a cycle of operation of the machine, and this cycle is subdivided into sixteen so-called cycle points. In Fig. 4 the period 20 in a cycle during which brushes 12 sense the 2, 1, 2, 5, value positions is shown in relation to the timing of closure of a number of cam operated contacts prefixed C, which are driven from a suitable shaft (not shown) in time with the card feed rollers to effect closure of the contacts at times indicated. The perforating code shown in Fig. 3 is such that a digit is represented in a perforating column by the perforation in that position which corresponds, or those positions 25 whose sum corresponds, to the digit to be represented.

The accumulator

45 In Fig. 1 the driving shaft 13 is suitably geared to the card feed rollers so as to make one revolution for each cycle of operation. For each denominational order of the accumulator, this shaft 13 has a gear 14 secured thereto which drives the adding clutch mechanism. The clutch driving mechanism is of the same construction as shown in Lake et al. Patent 2,328,653 and includes a ratchet 15 which is free on post 16 and integral with a gear 17 driven by gear 14 (Fig. 2). Rotatably carried by post 16 is a disk 20 having ten teeth 20a adapted to be engaged by tooth 21a on

the long arm of a clutch lever 21 to hold the disk against rotation in a counterclockwise direction.

At the side of disk 20 is a register or adding wheel 24 rotatable on post 16 and provided with ten peripheral notches 24a. Wheel 24 may take any of ten rotative positions with the values 0, 1 . . . 9. A spring pressed lever 25 engages with a notch 24a of wheel 24 to hold the wheel immovably and to center it in the value position into which it has been rotated. A transfer cam 26 is fixed to the side of wheel 24 and a stud 27 in wheel 24 extends through an opening in disk 20 to pivotally carry a clutch dog 30. A spring 31 urges the tooth of dog 30 to engage ratchet 15. In the positions shown in Fig. 1, the clutch lever 21 is in declutching position, its tooth 21a is restraining rotation of disk 20 counterclockwise and dog 30 is clear of ratchet 15. The dog 30 is being held clear of the ratchet by coaction of a pin 30b on the dog with a cam edge 20b of disk 20.

When the clutch lever 21 is dropped to cause its tooth 21a to release the disk 20 for counterclockwise movement, the spring 31 is effective to rock the dog 30 into engagement with ratchet 15. During this movement of the dog 30, its pin 30b rides along the cam edge 20b and cams the disk counterclockwise until its tooth 20a previously engaged by tooth 21a is to the right of the latter tooth. The parts are then in the clutching position shown in Fig. 2, and the register wheel 24 is coupled to the driving device 15, 17 for rotation. Through engagement of the pin 30b of the dog 30 with cam edge 20b, the disk 20 is forced to rotate counterclockwise together with the register wheel.

When the clutch lever 21 is returned to upper declutching position, its tooth 21a intercepts a tooth 20a of disk 20 and stops the disk. Register wheel 24 and dog 30 continue rotating while cam edge 20b of disk 20 cams the pin 30b outwardly until it is again in its outer position. As the pin 30b is cammed outwardly, clutch dog 30 moves clear of ratchet 15 and declutches the register wheel from the driving means. The register wheel is then held and centered in its new value position by lever 25. A spring urged latch 35 serves to hold lever 21 in either clutching or declutching position.

The clutch lever 21 has a short arm swiveled to the lower end of an armature 36 which is disposed between an advanced magnet AM and a stop magnet SM. Energization of magnet AM rocks armature 36 clockwise to lower lever 21, and energization of magnet SM rocks armature 36 counterclockwise to raise the lever 21.

When the wheel 24 is in its 0, 1 . . . 8 positions, the cam 26 holds a carry lever 37 pivoted at 38 in the position shown in Fig. 1 where a contact blade 39 (insulated from lever 37) takes a mid-position between contact elements 40 and 41. When the wheel is in its 9 position, a tooth on lever 37 is dropped into a cut 26a of cam 26 and blade 39 contacts element 41. When the wheel 24 passes from the 9 to 0 position, a rise 26b rocks lever 37 to cause blade 39 to engage element 40. When the lever is so rocked, an arm 42 integral therewith is engaged and held by a spring urged latch 43 which maintains the contact engagement between 39 and 40 until a pin 44 in gear 14 strikes an arm 45 integral with the latch 43 to release lever 42. The point in the cycle at which such unlatching occurs is indicated in the time chart in Fig. 4. The accumulator is also provided with a mechanical knock-off or declutching mechanism which comprises three pins 51, 52 and 53 secured

to the side of gear 14 and adapted during rotation of gear 14 to ride in succession under an edge of clutch lever 21.

Assume the clutch lever to be in lower position, 5 when either pin 51, 52 or 53 engages lever 21 it cams it upwardly into the position of Fig. 1. The knock-off pins 51, 52 and 53 are effective at fixed points of the cycle as indicated in the diagram Fig. 4.

10

Circuit diagram

The manner in which digital values are entered will now be explained in connection with the circuit diagram (Fig. 3) in which plug connections 61 are made between brushes 12 and sockets 62. Current is first placed on main lines 63 and 64 from a suitable source and, as the card 10 moves past brushes 12, it closes the usual card lever contacts 65.

15

The circuits involved in the entry of the several digits will be separately explained in the following.

20

Digit 1.—The perforation representing digit 1 is made in the 1 index point position and, when this position is at brushes 12, a circuit is traceable from line 64, contacts 65, roller 66, 1 hole in the card, brush 12, connection 61, socket 62, magnet AM to line 63. One step or cycle point later, contacts C2 close to energize all the SM magnets in parallel, so that the coupled wheel is interrupted after one step to enter a 1 therein.

25

Digit 2.—For digit 2, the start impulse to magnet AM occurs a step earlier so that the wheel advances two steps before magnets SM are energized.

30

Digit 3.—In this case the start and stop impulses occur the same as for the digit 1 except that a second impulse is sent to magnet AM through the second 2 hole concurrently with the 40 stop impulse from contacts C2. Since at this time the armature 36 (Fig. 1) is already against the core of magnet AM, concurrent impulses to the AM and SM magnets of the same order will not result in declutching of the accumulator wheel.

35

The reason for this is that the force of attraction exerted by the AM magnet on armature 36 will be greater than that exerted by the SM magnet, because of the air gap between armature 36 and the core of the SM magnet. Thus, in the 50 present case, the impulse to magnet SM will be ineffective to interrupt rotation of the wheel. Two steps later, after a total of three steps of rotation, pin 51 will strike lever 21 and effect positive mechanical uncoupling. For digit 4, the 55 action is as explained for digit 3 except that the start impulse occurs one point earlier for a total advance of four steps.

40

Digits 6, 7, 8 and 9.—For these digits the operation is the same as for digits 1, 2, 3 and 4 respectively with an additional component entry of five steps occurring later as indicated in Fig. 4; that is, when the 5 hole is sensed, the magnet AM is again energized and five steps later pin 52 effects mechanical uncoupling.

45

Digit 5.—For this digit, there is just a 5 hole which energizes the AM magnet five steps before pin 52 effects the knockout action.

50

Digit 0.—The digit 0 is represented by the second 2 hole and, since this completes a circuit to magnet AM concurrently with the circuit to magnet SM through contact C2, the wheel remains uncoupled since the armature is against the core of magnet SM and the greater attraction is in the direction to maintain the uncoupling condition.

Tens carry.—The tens carry circuits are the same as previously employed in this type of accumulator and are indicated in the circuit diagram, and the time of operation is shown in Fig. 4. There it is represented that contacts C3 first close to prepare the connections between successive orders so that, when contacts C1 close, if any wheel has passed through 0, a circuit is completed through contacts 40, 39 and C3 of the magnet AM in the next higher order. If this order happens to stand at 9, the circuit branches through its contacts 41, 39 to magnet AM in a still higher order.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a cyclically operable accumulating mechanism of the type wherein the digit entry in an accumulator element is initiated by an impulse transmitted to a start magnet and is terminated by an impulse transmitted to a stop magnet, and wherein concurrent impulses to both start and stop magnets will be ineffective to cause either initiation or termination of an entry, the combination of record controlled means for selectively transmitting an impulse to the start magnet at any of a plurality of predetermined points in a cycle of operation of the accumulator, and cyclic means for invariably transmitting an impulse to the stop magnet at one of said predetermined points, the concurrent occurrence of a record controlled start impulse at said one predetermined point being ineffective to cause initiation or termination of an entry.

2. In a cyclically operable accumulating mechanism of the type wherein the digit entry in an accumulator element is initiated by an impulse transmitted to a start magnet and is terminated by an impulse transmitted to a stop magnet, and

wherein concurrent impulses to both start and stop magnets will be ineffective to cause either initiation or termination of an entry, the combination of record controlled means for transmitting an impulse to the start magnet at a predetermined point in a cycle of operation to initiate an entry into the accumulator, cyclic means for transmitting an impulse to the stop magnet at a later point in the cycle, said record controlled means selectively transmitting a second impulse to the start magnet at said later point to negative the effect of the energization of the stop magnet, and means for terminating the entry at a still later point in the cycle.

3. In a cyclically operable accumulating mechanism of the type having an accumulator wheel and driving mechanism therefor provided with a coupling device and an uncoupling device for respectively starting and stopping the rotation of the wheel, and in which concurrent operation of said devices will render the coupling device ineffective if the wheel is at rest and will render the uncoupling device ineffective if the wheel is in motion, the combination of record controlled means for causing an operation of the coupling device at a predetermined point in a cycle of operation to initiate rotation of the wheel, cyclic means for causing operation of the uncoupling device at a later point in the cycle, said record controlled means selectively causing a further operation of the coupling device at said later point to render the uncoupling device ineffective, and means for effecting uncoupling at a still later point in the cycle.
